TILTABLE ADJUSTABLE SANDING WHEEL

Charles Jones, High Point, N. C., assignor to
 Pearson Sanding Machine Company, High
 Point, N. C.

Application September 7, 1937, Serial No. 162,781

2 Claims. (CL. 51—102)

This invention relates to wood working machines, and particularly to machines known as sanding machines wherein a sanding wheel is supported on a rotating shaft, and against which the work is held during the sanding operation.

The primary object of the invention is to provide a machine of this character including a motor operated shaft on which the sanding wheel is mounted, means being provided for adjusting the motor and its shaft, so that the motor may be moved from a horizontal position to a vertical position, or to intermediate angular positions, at the will of the operator.

Another object of the invention is to provide a sanding wheel of this character wherein the motor and sanding wheel may be securely held in their positions of adjustment.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a side elevational view of a sanding machine constructed in accordance with the invention.

Figure 2 is a front elevational view thereof.

Figure 3 is a view in elevation of the motor support.

Figure 4 is a sectional view taken on line 4—4 of Figure 1.

Figure 5 is a sectional view taken on line 5—5 of Figure 2.

Figure 6 is a fragmental plan view of the machine, illustrating the stationary table top.

Referring to the drawings in detail, the machine embodies a frame indicated generally by the reference character 5, the frame having a stationary table or top 6, which is formed with a circular opening 7 that is of a diameter slightly greater than the diameter of the sanding wheel 8.

This sanding wheel is mounted on the free end of the motor shaft indicated at 9, which shaft extends from the motor 10, in the usual and well known manner. An opening indicated by the reference character 11 extends from one edge of the table 6, and terminates at the opening 7, so that the motor shaft 9 may swing therethrough, when the motor is swung from a vertical position, to a horizontal position.

The reference character 12 designates a supporting shaft which is mounted on the frame of the machine 5, the shaft 12 being mounted in suitable bearings of the leg members of the frame. Mounted on one end of the shaft 12 is a pinion 13 that meshes with the worm 14, mounted on one end of the shaft 15, there being provided a crank handle 16, on one end of the shaft 15, whereby the shaft 15 may be rotated to rotate the shaft 12, for purposes to be hereinafter more fully described.

The motor support, includes a base plate 17 that is formed with ribs 18 disposed along its longitudinal side edges. This base plate 17 is mounted on the shaft 12, through the medium of 15 the bracket 19 that is bolted to the base plate 17, by means of the bolts 20. This bracket 19 is secured to the shaft 12, by means of the set screw 21, with the result that the motor may be accurately positioned with respect to the shaft 12. 20

Plate 22 also forms a part of the motor support, and is provided with beveled side edges, fitted under the ribs 18.

One end of the base plate 17 extends at right angles, where it is provided with an opening 25 through which the threaded shaft 23 extends, the shaft 23 also extending through a threaded opening in the plate 22, as clearly shown by Figure 5 of the drawings. On one end of the shaft 23 is a crank handle 24 whereby the shaft 23 30 may be readily rotated to move the plate 22 of the motor support, longitudinally of the base plate 17, to adjust the motor with respect to its support.

The reference character 25 designates the 35 bench or work rest forming a part of the machine, and as shown, this bench or work rest 25 includes a bracket 26 that extends downwardly and is provided with an extension 27 formed with a threaded opening, through which the threaded shaft 28 extends. This shaft 28 is supported in the lug 29 extending from the frame of the machine, the shaft 28 being provided with a hand wheel 30, whereby the shaft 28 may be rotated. It is obvious that when the shaft 28 is rotated, the bench or work support 25 will be moved vertically, so that the work may be supported on the bench 25 in an adjusted position, with respect to the sand wheel.

A set screw indicated by the reference character 31 extends through the extension 27, and is adapted to engage the shaft 28, securing the bench or work support 25, in its adjusted positions.

As clearly shown by Figure 2 of the drawings, 55

2

2,182,725

the bracket 26 of the bench or work support 25, moves under the flange plates 32 that are secured to the frame of the machine, the plates 32 acting as guides for the bracket 26 of the bench or work support 25.

From the foregoing it will be understood that due to the construction shown and described, the sanding wheel may be readily and easily moved from a vertical position as shown by Figure 1 of the drawings, to a horizontal position, wherein the shaft 9 operates in parallel relation with the bench or work support 25, adapting the device for use in sanding articles wherein it is necessary to support the articles at various angles with respect to the sanding wheel.

I claim:

1. In a sanding machine, a frame, including a table having an opening extending inwardly from one edge thereof, a motor support including a base plate having flanges formed along the edges thereof, said flanges forming guides, a slide slidably mounted on the base plate, the side edges of the slide moving under the flanges, said slide having a threaded bore, a threaded shaft sup-

ported on the base plate and movable in the threaded bore, a motor mounted on the slide, a shaft driven by the motor and adapted to swing through the opening, a grinding wheel on the shaft, said threaded shaft adapted to be rotated for adjusting the motor and shaft with respect to the table, and means for swinging the motor and motor shaft from a vertical position to a horizontal position.

2. In a sanding machine, a frame, a table forming a part of the frame and having an elongated opening extending to one edge thereof, a vertically adjustable pivoted support mounted on the frame, a motor mounted on the support and adapted to swing laterally with respect to the table, a shaft extending through the table and adapted to move laterally through the elongated opening to assume a horizontal position, a sanding wheel on the free end of the shaft, and means for swinging the motor laterally whereby the sanding wheel may be operated in various positions from a vertical to a horizontal plane.

CHARLES JONES.

DISCLAIMER

2,182,725.—*Charles Jones*, High Point, N. C. TILTABLE ADJUSTABLE SANDING WHEEL. Patent dated December 5, 1939. Disclaimer filed February 10, 1943, by the assignee, *Pearson Sanding Machine Company*.

Hereby enters this disclaimer to claim 2 in said specification.
